DOBBY SPRING FOR LOOM HARNESS MECHANISMS

Filed June 20, 1929

Inventor:
Homer F. Livermore.
by *Charles S. Gooding*, At't'y.

UNITED STATES PATENT OFFICE

HOMER F. LIVERMORE, OF BROOKLINE, MASSACHUSETTS, ASSIGNOR TO H. F. LIVERMORE CO., OF ALLSTON, MASSACHUSETTS, A CORPORATION OF MASSACHUSETTS

DOBBY SPRING FOR LOOM HARNESS MECHANISMS

Application filed June 20, 1929. Serial No. 372,383.

This invention relates to a spring and particularly to a doby spring and means by which said spring is connected to the harness of a loom.

5 The object of the invention is to provide a spring of the character mentioned together with a wire by means of which said spring is attached to the bottom of a harness, the spring and wire being permanently connected together in a manner to permit a relative longitudinal movement between the spring and wire, it being impossible for the wire to be either pulled out of the spring or to fall into the spring beyond a predetermined 15 point.

The invention consists in a spring and harness connection therefor as set forth in the following specification and particularly as pointed out in the claims thereof.

20 Referring to the drawings:

Figure 1 represents a front elevation of a spring and harness connection therefor embodying my invention, a portion of the spring being broken away to save space in the drawings, and another portion of the spring being broken away and illustrated in section.

Fig. 2 is a view similar to Fig. 1 illustrating a modified embodiment of the invention.

Like numerals refer to like parts throughout the several views of the drawings.

In the drawings, referring particularly to Fig. 1, A represents a helical spring having a tapered portion *a* at one end thereof and an eye *b* at the other end thereof. Loosely mounted within the spring A and protruding from the tapered end *a* thereof is a wire 1 and the end portion of said wire that is located within the spring A has an enlarged portion preferably a loop 2 formed thereon, the diameter of which is such that it cannot be pulled through the tapered end of the spring. At its other end the wire 1 is bent to form a hook 3 which may be attached to a suitable connection provided upon the harness.

At a suitable location between the loop 2 and hook 3 the wire 1 is bent laterally to form an offset portion 4 of sufficient size to prevent the wire from being moved into the 50 spring beyond a shoulder 5 which is formed

by the offset portion, and it is evident that the loop 2 and offset portion 4 will permit a relative longitudinal movement between the spring A and wire 1, it being impossible to pull the wire outwardly through the tapered end *a* of the spring because of the presence of the loop 2 in said tapered end or for the wire to drop downwardly into the spring beyond the shoulder 5.

It will furthermore be evident that the spring may be lifted independently of the wire 1 when the latter is attached to a harness until the upper extremity of the spring contacts with the shoulder 5.

In Fig. 2 I have illustrated a modified embodiment of my invention in which a wire 6 is connected to a spring A by means of a loop 7 which engages the tapered end portion *a* of the spring, and a hook 8 is formed at the opposite end of said wire from the loop 7. At an intermediate point of the wire an enlarged portion 9 is provided of sufficient diameter to form a shoulder 10 which is adapted to contact with the extremity of the spring A and prevent the rod 6 from being moved inwardly into said spring beyond said shoulder.

It is evident that the enlarged portion 9 may be formed integral with the wire 6 or said portion may constitute a collar which may be secured to the wire in any suitable manner. In all respects, the functions that are performed by the enlarged portion 9 and shoulder 10 are identical with the functions that are performed by the offset portion 4 and shoulder 5 previously described.

I claim:

1. In combination, a coil spring provided with a reduced end portion and a wire loosely mounted therein and projecting from said reduced end, said wire being provided with means at one end thereof to prevent the removal of the wire from said spring through said reduced end, and an offset portion embodied in said wire intermediate the ends thereof adapted to contact with the extremity of the spring and limit the relative longitudinal movement between the wire and spring.

2. In combination, a coil spring provided

with a reduced end portion and a wire loosely mounted therein and projecting from said reduced end, said wire being provided with a loop at one end thereof adapted to prevent the removal of the wire from said spring through said reduced end, said wire also being provided with a shouldered portion intermediate its ends adapted to contact with the extremity of the spring and limit the relative longitudinal movement between the wire and spring.

3. In combination, a coil spring provided with a tapered end portion and a wire loosely mounted therein and projecting from said tapered end, said wire being provided with means at one end thereof adapted to prevent the removal of the wire from said spring through said tapered end, said wire also being provided with a laterally bent offset portion intermediate its ends adapted to contact with the extremity of the spring and limit the relative longitudinal movement between the wire and spring.

In testimony whereof I have hereunto set
25 my hand.

HOMER F. LIVERMORE.
